OF D 12,501

DESIGN FOR WALL-PAPER.

Design No. 12,501, dated September 27, 1881.

UNITED STATES PATENT OFFICE.

EDUARD LEISSNÈR, OF NEW YORK, N. Y., ASSIGNOR TO LEISSNÈR & LOUIS,
OF SAME PLACE.

DESIGN FOR WALL-PAPER.

SPECIFICATION forming part of Design No. 12,501, dated September 27, 1881.
Application filed August 25, 1881. Term of patent 3½ years.

To all whom it may concern:

Be it known that I, EDUARD LEISSNÈR, of New York, in the county and State of New York, have invented a new and original Design for Wall-Paper, of which the following is a specification.

This invention relates to a new and original design for wall-paper and similar fabrics; and it consists in the novel grouping and configuration of parts, hereinafter more fully described.

The accompanying photograph illustrates a face view of a wall-paper having my new design.

Between two borders, *o o*, each of which is 15 ornamented by an undulating vine and intervening beads, is the large scroll *A*, which is formed into convolutions to give room for ornaments *B D*.

B is a large rosette-like flower, and near it 20 are bud-like figures *a*, projecting from the vine.

The stem of the vine also contains peculiar scroll-leaves *b*, as shown. Near the figure *B* projects, from the vine or main scroll *A*, another scroll, *e*.

The figure *D* represents a large peony-shaped 25 flower, and near it is a group, *d*, of lesser flowers, from which extends a stem bearing a flower near the vine *e*.

I claim—

1. The design for wall-paper, consisting of 30 the scroll *A*, groups *B D*, and ornaments *a b d e*, substantially as shown.

2. The design for wall-paper, consisting of the scroll *A*, groups *B D*, ornaments *a b d e*, and borders *o o*, substantially as shown.

EDUARD LEISSNÈR.
